FIG. 1

The dot-dash lines on the drawing indicate that the rows of keys extend across the keyboard.

I claim:

The ornamental design for a typewriter or the like, substantially as shown and described.
